UNITED STATES PATENT OFFICE.

FRANK H. CARROLL, OF DENVER, COLORADO.

CONDIMENT-HOLDER.

1,253,465.

Specification of Letters Patent. Patented Jan. 15, 1918.

Application filed January 22, 1917. Serial No. 143,757.

To all whom it may concern:

Be it known that I, FRANK H. CARROLL, a citizen of the United States, residing at Denver, in the county of Denver and State of Colorado, have invented new and useful Improvements in Condiment - Holders, of which the following is a specification.

My invention relates to a combined condiment holder which is particularly adapted 10 for use as a salt and pepper container and distributor. Objects of the invention are: holding in one receptacle both salt and pepper, or a plurality of other condiments, each of which is contained in separate non-communicating compartments; free and independent distribution, or egress, of either substance from the holder as desired; convenience in obtaining both salt and pepper together, especially to patrons of hotels, 20 restaurants, and other public eating places; economy in the quantity of materials consumed in manufacture; saving in space, and saving in time when refilling or cleaning; protection of contents from atmospheric 25 effects, thus preserving the strength of same, and also from contamination by foreign agencies, such as dust, germs, etc.; and the elimination of any possibility of spilling contents, particularly when the holder is 30 carried in lunch baskets while on camping or automobile trips, and the like.

Reference is here made to the accompanying drawing, which comprises a part of these specifications, and in which like numbers refer to similar parts in the several views:

Figure 1 is a perspective view of the double compartment body or vessel of the condiment holder; Fig. 2 represents a side 40 elevation of the cover or cap to the holder; Fig. 3 is a top plan view of the cap; and Fig. 4 is a plan of the under side of cap.

To describe my invention more in detail, the condiment holder consists of receptacle 1, which is divided into two separate and non-communicating compartments by a centrally disposed partition 2, as shown in Fig. 1. This partition 2, which is preferably an integral part of container 1, extends to the 50 bottom of the latter, and the top edge of same is horizontally flush with the top edge of said container.

On one side of the holding receptacle 1, near the top edge, an exteriorly disposed

bead 3, with a central bore, is provided, into 55 which the ends of member 7 shown in Figs. 2, 3 and 4 are inserted, and diametrically opposite, in similar position, is another projecting bead 4, over which the member 8, Figs. 2, 3 and 4, firmly clamps when the 60 cap to the holder is closed.

Although that portion of the invention shown in Fig. 1 is illustrated in cylindrical form, it is not necessary to adhere to this form in its manufacture, since the entire device is so conceived as to permit its construction in varying shapes and styles of almost any number, as can be readily seen. The materials used in manufacture may be either metal, wood, china, glass, crockery, porcelain, or any other suitable substance.

In Figs. 2, 3 and 4 of the attached drawing the member 5 consists of a perfectly flat plate, perforated with a suitable number of holes 16 through which the contents of the 75 holder may be sifted. On the under side of this plate 5 a thin layer of cork 6, or composition, is provided, the position of same being clearly illustrated in Fig. 4. This cork or composition layer 6 is fastened to plate 5 80 either by cement or by means of the shouldered recess 15, and its purpose is to provide an effective seal when the lid of the holder is closed down, thus preventing leakage or intermingling of contents of the 85 two separate compartments in container 1.

Members 8 and 9 are integral parts of plate 5, the former (8) being a depending spring catch which clamps snugly over projection 4 when the cover is closed, and the 90 latter (9) comprising a loop through which the member 7 passes, as illustrated. It is obvious that the function of members 3, 7 and 9 is to provide a hinge on which the cover of the holder is operated in the opening and closing process. This hinge arrangement constitutes a distinct advantage 95 over the screw or push cap type of condiment holder in that it permits the opening and closing of the holder with the minimum 100 amount of effort and time, and at the same time insures the replacement of the cap over the container in proper position so as to effect a perfect seal, and allow the sifting of either condiment in the container through 105 the apertures specifically provided therefor.

While I consider the type of hinge shown in the drawing most suitable when the con-

tainer proper is made of glass, china, or like materials, it will be understood, of course, that a hinge of any other commonly known type may be employed, if desired, in the manufacture of the holder.

On the upper or top side of perforated cap 5 I provide two vertically extending lugs or ears 14, diametrically opposed to each other, and positioned near the outer edges of cap 5 as illustrated in Fig. 3. These lugs 14 are connected by a rod or pintle 13, the middle portion of said rod being encircled with a single coil spring 12, the ends of which extend outwardly in opposite directions as indicated in the drawing. Flaps 10 are provided for the purpose of covering and sealing apertures 16, same being pivotally mounted on rod 13, and actuated by lever arms 11, which are integral parts of said flaps. Thus it will be seen that by exerting pressure on either lever arm, the flap of which that arm forms a part is raised, thereby uncovering the perforations in one side of cap 5 and allowing the contents of that particular half of the holder to be sifted or shaken out; also that downward pressure exerted on one arm causes simultaneously a reflex pressure on the under side of the companion arm through the medium of the single coil spring 12, thus insuring proper closure of one side while the opposite side is being opened. The main function of coil spring 12, however, is to keep both flaps 10 closed when the holder is not in use, and to automatically close either flap immediately

upon releasing pressure from the connected lever arm.

In order to facilitate use of the holder the initials of the condiments contained therein may be stamped on the lever arms or flaps; for example, when the holder contains salt and pepper, the letters "S" and "P" may be placed on the members indicated in suitable positions.

I claim:—

A condiment holder capable of being constructed in varying styles, having a receptacle open at one end, a partition dividing said receptacle into two separate non-communicating chambers, a projecting bead on the outside and near the top edge of said receptacle, a perforated removable cap to cover the open end, provided with a hinge at one side and a depending spring catch at the opposite side, said cap being further provided with two vertically projecting lugs on the upper side, a pintle connecting the said lugs two separate closure flaps pivotally mounted on said pintle, each having a lever arm, a single coil spring also mounted on said pintle with the ends thereof extending in opposite directions directly under the lever arms and serving to keep the flaps closed over the aforementioned perforations when in normal position, and a cork or composition pad attached to the under side of the said perforated cap for the purpose of effectively sealing the open end of the container when the cap is closed.

FRANK H. CARROLL.
